DEVICE FOR APPLYING LIQUID ADHESIVE
TO PAPER AND SIMILAR MATERIALSAlfred Winkler and Max Dünnebier, Neuwied,
GermanyApplication October 3, 1935, Serial No. 43,434
In Germany May 25, 1934

12 Claims. (Cl. 91—43)

The invention relates to a device for applying liquid adhesive to paper and similar materials. In particular it is an object of the invention to enable liquid adhesive of all kinds to be applied satisfactorily by the so-called echelon or stepped layer process even in cases in which blanks for the production of envelopes or bags or other sheets of paper or similar material which are laid, in stepped arrangement, one on top of another and one beyond another with their edges a given distance apart, have to be provided, in one working operation, without altering either the stepped formation of the layer of sheets or the direction of motion of such layer, with a coating of adhesive applied, in the case of each individual sheet, to its opposite margins as exposed on the two opposite sides of the stepped layer.

With such a method of working and such a stepped arrangement of the sheets (said arrangement being shown, for instance, in the drawing of application Serial No. 13,510, filed March 28, 1935, for Letters Patent of the United States of America) the layer of sheets can be guided along past one of the adhesive applying devices in such a fashion that those surface portions of the sheets on one side of the said layer which, by reason of the stepped arrangement, are exposed, so that they can be served with adhesive, lie to the rear, having regard to the direction of motion of the layer. For the application of the adhesive to these rearwardly located surface portions of the sheets one of the adhesive applying devices ordinarily used for the stepped layer gumming process can be employed. When, however, after leaving such an adhesive applying device, the layer of sheets is carried along further in the same direction and in the same stepped formation the exposed surfaces upon the other side of the layer, which surfaces also have to take a coating of adhesive, must, of necessity, lie one ahead of another, having regard to the direction of motion of the layer. Consequently, the outer edges of these exposed surface portions of the sheets are the foremost parts to encounter the device which applies adhesive to this side of the layer. Adhesive applying devices as commonly used in the stepped layer gumming process cannot, therefore, be employed in this case, as the advanced edges of the sheets would collide with the edges of such devices, causing damage to the blanks and frequent derangements in the working of the machine as a whole.

On this account, for the purpose under consideration, devices have been proposed in which

the application of the adhesive is effected by a rotating applicer roll, which makes contact with the stepped layer of sheets and which takes up the adhesive from a dipper roll running in an adhesive container.

Such adhesive applying devices, apart from their relatively complicated construction, have the disadvantage that they require very careful minding. First and foremost, care must be taken that, when the machine as a whole is temporarily shut down, so that the stepped layer of sheets is also stopped, the adhesive shall not dry up on the rolls of the adhesive applying device, as this would jeopardize the satisfactory working of the latter. Consequently, when the complete machine in which they are employed is temporarily shut down, these adhesive applying devices must not only continue to run uninterrupted, so that the adhesive may not have an opportunity of solidifying on the rolls, but they must also be lifted off the layer of sheets each time the whole machine and the said layer of sheets is stopped, in order to prevent the blanks from being smeared with adhesive. In addition, after every protracted shut-down of the whole machine the adhesive container has to be emptied and the rolls carefully cleaned.

The risk of solidification or setting of the adhesive on the rolls of the adhesive applying device in question is particularly great when working the so-called "dry adhesive" for "plastic gumming", as this dries with extraordinary rapidity when, in the form of a thin layer on the rolls, it is exposed to air. The rapidly drying adhesive substance then assumes a viscous consistency and, under the rubbing action of the rolls, turns into more or less fine crumbs which deposit themselves on the surfaces of the blanks to be provided with adhesive coatings. An adhesive coating permeated in this way with crumbs is naturally unsatisfactory and, in most cases, completely useless.

The present invention provides an adhesive applying device which can be used in connection with either of the two aforementioned positions of the exposed adhesive-receiving surfaces of the stepped sheets but, above all else, in the case in which the sheet surfaces to be provided with adhesive lie advanced in the direction of motion of the layer of sheets, use of this device not only avoids disturbances in working due to the sheets arriving at the device edge first but also obviates the aforementioned defects of adhesive applying devices operating with rolls.

Important features of the adhesive applying

device according to the invention reside in the adhesive container. This adhesive container has, on that side of it which is turned towards the stepped layer of sheets, a narrow slit for the outflow of adhesive and this slit, at its outlet, lies close against the layer of sheets. The course or path followed by this slit from the interior of the container to its outlet opening on the layer of sheets, is such that the said path forms an acute angle with the direction from which the stepped layer of sheets advances. Furthermore, that outer surface of the adhesive container which is turned towards the stepped layer of sheets, has a rounded off or inclined part in front of the adhesive outlet slit on the side from which the layer of sheets advances, this part gradually receding from the said layer the farther it goes from the edge of the outlet slit.

One result of this construction of the adhesive applying container is that the adhesive emerging from the slit thereof does not meet the sheets perpendicularly and, therefore, does not have the tendency to come out in both directions. In other words, it does not tend to emerge in the direction opposed to that in which the sheets travel, which, with the surfaces to be coated lying advanced in the direction of motion of the sheets, would permit of its entering beneath the advanced edges of the individual sheets. On the contrary, by reason of the described course taken by the outlet slit, the adhesive, on its emergence, already has a direction of flow corresponding and suited to the direction of travel of the layer of sheets. On the other hand, the rounding off or sloping off of the outer surface of the container, starting from the edge of the outlet slit on the side from which the sheets advance and gradually receding from the layer of sheets permits of the unimpeded passage beneath the container of the edges of the sheets which lie advanced in the direction of motion. Furthermore the course of the outlet slit according to this invention affords the advantage that the rear edge of the slit, which the edges of the sheets meet last on their way under the container is blunt, this edge being formed by two planes which meet each other at an obtuse angle. Thus, even under this edge, the sheets can enter without impact. A slight rounding off of the slit-edge in question enhances this favourable effect.

Finally a further advantage is to be observed in the fact that, having regard to the direction of feed of the stepped layer of sheets, only a narrow strip of the outer surface of the adhesive container rests on the said layer to the rear of the outlet slit, while the outer surface of the container behind this strip recedes sharply from the layer of sheets. When used for so-called plastic gumming, that is to say, the application of dry adhesive to the work pieces, this arrangement is especially well adapted for preventing freshly applied adhesive, while still in moist condition, from having to drag beneath and rub against a relatively large surface of the container, whereby the aforementioned risk of the rapidly drying adhesive turning into crumbs is avoided.

For the application of adhesive to the exposed parts of the sheets which lie advanced in the direction of motion of a stepped layer of sheets a guide plate is arranged, according to the invention, ahead of the adhesive container, that is to say, on the side thereof from which the sheets approach and overlie the stepped layer. The leading edge of this guide plate comes as close

as possible to that rounded-off or chamfered-off outer surface of the adhesive container which immediately precedes the outlet slit. Starting from this leading edge, the surface of the guide plate rests lightly against some of the stepped sheets and thence recedes quite gradually from the layer of sheets. At its rear edge it is spaced from the layer only far enough to ensure that the exposed leading edges of the sheets will run under it. In the case of blanks which, on account of their shape, have to expose a considerable amount of surface behind their coating of adhesive and up to the region where it is possible for them to be engaged by the conveying or delivering means, the guide plate aforesaid both guides and stiffens the exposed surface portion, so that any slight resistance that may act on such surface or upon the leading edge thereof does not immediately cause derangement but can be overcome, notwithstanding the pushing action of the conveying means taking effect at a considerable distance from the leading edge of the sheet.

It is a further object of the invention to provide an arrangement which serves to blow compressed air on to the surface portions of the sheets which lie advanced in the direction of motion of the stepped layer of sheets and have been provided with an adhesive coating. This counteracts the curling up and buckling which frequently takes place at these parts and which may have a particularly harmful effect when, as aforementioned, there is a relatively large area of sheet exposed between the leading edge of each sheet and the means which holds and delivers it, since these exposed surface portions can easily get out of place in the stepped layer of sheets and give rise to disturbance in working.

Two constructional embodiments of adhesive applying devices in accordance with the invention are shown, by way of example, in Figs. 1 and 2 of the accompanying drawings, each of these views showing a vertical section through the device which it depicts. Fig. 3 is a view mainly of the conveying and guide means for the layer of blanks, as seen from the right hand side of Fig. 1 or Fig. 2, the actual adhesive container or gum box being omitted.

The direction of feed of the stepped layer of sheets B is indicated, in all figures of the drawings, by an arrow and is assumed to be such that the adhesive receiving surfaces 2, exposed between the stepwise arranged edges 1 of the individual sheets, are the first parts of the sheets to reach the adhesive container 3 or 19, at which they arrive edge first, so that, actually the edges 1 themselves meet the container first. Obviously these edges 1 must meet and travel past the container without impact and without retardation, if derangement of and damage to the blanks is to be avoided and a satisfactory coating of adhesive obtained.

The cross-sectional forms depicted in Figs. 1 and 2 of the drawings for the adhesive containers 3 and 19 are simply in the nature of examples and quite different shapes can be selected without departing from the essential features of the invention. Moreover, the means for fixing the containers 3 and 19 and for pressing them against the stepped layer of sheets are to be assumed to be known per se and of no importance so far as the present invention is concerned; consequently they are not reproduced in the drawings.

Important features of the invention reside in the arrangement of the outlet slit 4 which is provided in the lower part of the container 3 of

Fig. 1 and through which the adhesive, filled into the container, emerges and reaches the free surfaces 2 of the stepped layer of blanks or sheets B; also in the formation of the outer surface of the container 3 immediately adjoining this outlet slit 4. According to the invention the substantially linear outlet slit 4 is so arranged that its course or path, starting from the interior of the container and opening on to the layer of sheets B, forms an acute angle with that part of the layer of sheets B which is running up to the container 3, that is to say, with the part lying at the bottom in the drawings. There is thus imparted initially to the adhesive emerging from the slit 4 a direction of outflow suited to the direction of feed of the layer of sheets B and this counteracts the tendency of the adhesive to penetrate beneath the edges 1 of the sheets in the layer. To obtain non-impactive entry of the edges 1 of the sheets, the outer surface of the container 3, starting from the edge 5 of the outlet slit 4 (the lower edge in the drawings and the one which is turned towards the side from which the sheets advance) is so formed by rounding it off or inclining it, that it recedes gradually at an acute angle from the layer of sheets B. In the example shown in Fig. 1 of the drawings, below the outlet slit 4 and under the actual bottom 6 of the container a special reinforcement 7 is provided whereby a pronounced rounding off is obtained under which the edges 1 of the sheets can comfortably run in without any danger of impact.

The edge of the outlet slit 4 which lies uppermost in the drawings and beneath which the edges 1 of the sheets arrive last on their way under the container, is formed by the narrow outer plane surface 8 and the upper internal plane surface of the slit 4, these two planes meeting each other at an obtuse angle α . Therefore, this edge is blunt, which, in itself, favours the non-impactive entry of the sheets. The unhindered entry of the sheets is, however, made all the more certain by a very slight rounding off of this edge of the slit.

Behind the last named edge of the slit, that is to say, on that side of the outlet slit 4 which is directed towards the departing portion of the layer of sheets B, only a narrow strip 8 of the outer surface of the container 3 (in fact, a blunt edge) rests on the stepped layer of sheets, so that the adhesive applied to the sheet surfaces 2 only needs to pass through under this narrow strip of surface 8 and is subjected to friction only by this strip, the friction, therefore, being so slight that it cannot have any harmful effect. Behind the narrow strip 8 of the outer surface of the container 3 this surface recedes sharply from the stepped layer of sheets B. The opening 9 in the wall of the container 3 serves for filling the latter with adhesive. When the whole machine and the layer of sheets are temporarily stopped the container does not need to be lifted off the said layer, as smearing of the blanks is not, in this case, to be feared. In order to permit of the outlet slit 4 being closed up if, for any reason, the container has to be lifted off the layer of sheets, a slide 10 is provided. It is guided, by means of slots 11, between the washers 12 and the heads 13 of the screws 14 fixed in the container wall. In an outwardly opening slot 15 in the turned over part 16 of the slide 10 there runs a groove formed in a screw 17 the thread of which is engaged in an angle bracket 18 provided on

the container 3 and this screw serves for adjusting the slide 10.

A simpler constructional form of the adhesive container is shown in Fig. 2. This container 19, however, exhibits the same novel features as the container 3 of Fig. 1. Here, again, the slit 20, for the outflow of adhesive, runs in the direction hereinbefore described and that part of the external surface of the container 19 which lies below this slit likewise recedes gradually from the stepped layer of sheets B. Above the slit 20 this container 19 also presents only a narrow strip 21 of its outer surface in effect, a blunt edge to the layer of sheets B and this narrow strip of surface 21 likewise makes an obtuse angle α with the upper internal surface of the slit 20.

A slide for shutting off the outlet slit 20 is not provided in the adhesive container 19, since the latter is mounted on two pins or trunnions 23, fixed to its side walls 22 and, when it is lifted away from the stepped layer of sheets B, can, therefore, be tilted in such a way that emergence of the adhesive from the slit 20 is no longer possible.

In the accompanying drawings it is assumed that the stepped sheets B, when they reach the adhesive container 3 or 19, have already been provided, by means of another arrangement, with a coating of adhesive applied to the exposed surface portions on the opposite side of the layer. The device according to the invention is intended, therefore, for the application of a second coating of adhesive, as required, for instance when employing dry adhesive, as aforesaid, for self-sealing articles. Thus, with certain forms of work pieces, for instance, envelope blanks, as shown in Fig. 3, the conveyor means for the blanks, (that is to say, the conveyor belt 24 and the counter rolls 25 and 26 co-operating therewith, which convey the layer of sheets B from the device which applies a coating of adhesive to the one side thereof, past a device which dries this coating and thence to the adhesive container 3 or 19) are preferably arranged only in the region of the side flaps 8 of the said blanks; otherwise they would come into contact with the coating of adhesive on the reverse side of the closure flap V. This arrangement of the conveyor means, however, has the drawback that that flap of each blank which lies advanced in the direction of motion and which subsequently forms the back part of the finished envelope is free over the whole of its length, as indicated by the dimension r in Fig. 3, when its leading edge is being pushed under the adhesive container 3 or 19, by means of the belts 24 and the counter rolls 26.

Thus, particularly in the case of thin papers, quite a small amount of resistance may cause this flap to ruck up and upset the whole arrangement. In order to counteract this, the guide plate 27 is located ahead of the adhesive container 3 or 19 and over the stepped layer of sheets, in such a way that it overlies practically all of the surface of the exposed flap of that blank which, at any given moment, is running in under the said adhesive container and that, within the confines of this surface, it rests lightly upon the layer of sheets. The guide plate 27, therefore guides and, what is more important, stiffens the free or exposed flaps of the blanks, thus enabling these flaps, when running in under the adhesive container, to overcome any resistance that may arise (so long as it is not extraordinarily great) without being held up and so rucked or crumpled.

In Fig. 3 for the sake of clearness, the adhesive

container itself is not shown; only the position of its outlet slit in relation to the stepped layer of sheets B is indicated by the narrow closely sectioned rectangle IV. The surface which lies above this in the figure and which is hatched with thinner and more widely spaced lines indicates the coating of adhesive which has already been applied. The guide plate 27 must be easily interchangeable with others, so that the size thereof may be adapted to the sizes of blanks to be operated on. In the example shown in the drawings a radially slit ring 28 on the guide plate is fixed, by means of a screw 29 upon a lug 30 projecting from a ring 31. The last named ring is freely rotatable on a cross shaft 34 upon which it is mounted between two locating rings 33 united by a yoke 32 and which is fixed in the side cheeks of the device although in Fig. 3, for the sake of clearness, it is shown broken away. The locating rings 33 are fixed by the screw 35 to the cross shaft 34. Between an arm 36 on the ring 31 and the yoke 32 which unites the two locating rings 33 there is arranged a light compression spring 37, so that the ring 31 presses the guide plate 27 against the stepped layer of sheets B. The amount of pressure exerted by the spring 37 can be varied, according to requirements, by turning the locating rings 33 upon the cross shaft 34.

30 The stepped layer of sheets B passes from the conveyor belts 24 to the conveyor belts 38, both of which engage the said layer with the aid of their counter rolls 39, such engagement again taking place only in the region of the side flaps S. 35 Between the conveyor belts 24 and 38 there is arranged a guide plate 41, which is fixed to a cross shaft 40 and over which the layer of sheets glides along. The conveyor belts 38 and their counter rolls 39 engage each individual blank at the 40 exact instant at which it is released by the conveyor belts 24 and the last counter rolls 26 of the latter. This is necessary because the conveyor belts 38 are driven just a little faster than the conveyor belts 24, so that, after the adhesive 45 has been applied, the blanks are drawn apart slightly, in order to prevent them from sticking together along their leading edges. In Fig. 3 this slight drawing apart is made apparent, in the case of the two foremost ones of the blanks already engaged by the conveyor belts 38, by narrow unhatched strips extending along in front of the leading edges.

Behind the adhesive container 3 or 19, having regard to the direction of motion of the stepped layer of sheets B, that is to say, in a region traversed by the exposed parts of the sheet surfaces which have just been coated with adhesive, there is arranged, at a little distance from the coated surfaces, at least one blower nozzle 42 55 through which a blast of air, taken from a suitable source, is directed on to the free and exposed marginal parts which have received the coating. The nozzle 42, as the drawings show, is disposed so as to project the air blast in a direction forming 60 an acute angle with the direction of travel of the stepped layer and the action of the blast is to force the exposed and free marginal portions, as they pass in succession, firmly against the subjacent sheets in the layer. This counteracts the 65 tendency of the adhesive-carrying marginal parts of the individual sheets to curl up or buckle, this tendency being more or less apparent according to the kind of paper used for the blanks and its consequence being that the said adhesive coated 70 marginal portions curl away from the layer of

75 sheets, which may prevent their being conveyed in a regular manner and so cause them to be damaged.

What we claim is:—

1. In apparatus for applying a coating of adhesive in liquid state to paper and similar materials and including an adhesive container with an outlet for adhesive and means for producing relative wiping action between that surface of the material which is to receive the adhesive coating and the said adhesive outlet, a container wherein the adhesive outlet is formed as a short duct of narrow slit-like and substantially uniform cross-section extending from the interior of the said container to the material-contacting exterior surface thereof in an upwardly inclined direction, forming an acute angle with the substantially vertical plane in which the material to be coated travels and arrives at the adhesive outlet. 10

15 2. In apparatus for applying a coating of adhesive in liquid state to paper and similar materials and including an adhesive container with an outlet for adhesive and means for producing relative wiping action between that surface of the material which is to receive the adhesive coating and the said adhesive outlet, a container wherein the adhesive outlet is formed as a short duct of narrow slit-like and substantially uniform cross-section extending from the interior of the said container to the material-contacting exterior surface thereof in an upwardly inclined direction, forming an acute angle with the substantially vertical plane in which the material to be coated travels to and arrives at the adhesive outlet. 20

25

30 3. In apparatus for applying a coating of adhesive in liquid state to paper and similar materials and including an adhesive container with an outlet for adhesive and means for producing relative wiping action between that surface of the material which is to receive the adhesive coating and the said adhesive outlet, a container wherein the adhesive outlet is formed as a short duct of narrow slit-like and substantially uniform cross-section extending from the interior of the said container to the material-contacting exterior surface thereof in an upwardly inclined direction, forming an acute angle with the substantially vertical plane in which the material to be coated arrives being shaped to recede gradually from the surface of said material. 35

40 4. In apparatus for applying a coating of adhesive in liquid state to paper and similar materials and including an adhesive container with an outlet for adhesive and means for producing relative wiping action between that surface of the material which is to receive the adhesive coating and the said adhesive outlet, a container wherein the adhesive outlet is formed as a short duct of narrow slit-like and substantially uniform cross-section extending from the interior of the said container to the material-contacting exterior surface thereof in an upwardly inclined direction, forming an acute angle with the substantially vertical plane in which the material to be coated travels to and arrives at the adhesive outlet, the exterior surface of said container on that side of the adhesive outlet from which the material to be coated arrives being shaped to recede gradually from the surface of said material. 45

50 5. In apparatus for applying a coating of adhesive in liquid state to paper and similar materials and including an adhesive container with an outlet for adhesive and means for producing relative wiping action between that surface of the material which is to receive the adhesive coating and the said adhesive outlet, a container wherein the adhesive outlet is formed as a short duct of narrow slit-like and substantially uniform cross-section extending from the interior of the said container to the material-contacting exterior surface thereof in an upwardly inclined direction, forming an acute angle with the substantially vertical plane in which the material to be coated travels to and arrives at the adhesive outlet, the exterior surface of said container being shaped. 55

60 6. In apparatus for applying a coating of adhesive in liquid state to paper and similar materials and including an adhesive container with an outlet for adhesive and means for producing relative wiping action between that surface of the material which is to receive the adhesive coating and the said adhesive outlet, a container wherein the adhesive outlet is formed as a short duct of narrow slit-like and substantially uniform cross-section extending from the interior of the said container to the material-contacting exterior surface thereof in an upwardly inclined direction, forming an acute angle with the substantially vertical plane in which the material to be coated travels to and arrives at the adhesive outlet, the exterior surface of said container being shaped. 65

70 7. In apparatus for applying a coating of adhesive in liquid state to paper and similar materials and including an adhesive container with an outlet for adhesive and means for producing relative wiping action between that surface of the material which is to receive the adhesive coating and the said adhesive outlet, a container wherein the adhesive outlet is formed as a short duct of narrow slit-like and substantially uniform cross-section extending from the interior of the said container to the material-contacting exterior surface thereof in an upwardly inclined direction, forming an acute angle with the substantially vertical plane in which the material to be coated travels to and arrives at the adhesive outlet, the exterior surface of said container being shaped. 75

on that side of the adhesive outlet from which the material to be coated arrives, so as to recede gradually from the surface of said material and, on that side of the adhesive outlet from which the coated material departs, so as to present only a narrow strip for contact with the coated surface.

5. In apparatus for applying a coating of adhesive in liquid state to paper and similar materials, an adhesive container having an outlet opening for adhesive, means for supporting material to be coated in juxtaposition to said adhesive outlet, means for producing relative wiping action between said adhesive outlet and that surface of the material which is to receive the adhesive coating therefrom and guide means acting upon said surface in a zone preceding that in which it receives the adhesive, said adhesive outlet consisting of a short duct of narrow slit-like and substantially uniform cross-section proceeding from the interior to the exterior surface of the adhesive container in an upwardly inclined direction, forming an acute angle with the substantially vertical plane in which the uncoated material travels to and arrives at the said adhesive outlet.

6. In apparatus for applying a coating of adhesive in liquid state to paper and similar articles arranged in stepped formation in a continuous layer, so that a defined surface portion of each article is exposed for coating, the combination with an adhesive container having a narrow outlet slit for adhesive and means for producing relative wiping action between the outlet slit of the container and that composite surface of the stepped layer of articles which is to receive the adhesive coating, of guide means acting directly upon the said composite surface in a zone preceding and immediately adjacent to the zone of application of the adhesive issuing from the slit and supporting means for said stepped layer of articles, said supporting means directly confronting both the adhesive outlet of the container and the guide means.

7. The apparatus defined in claim 6, further characterized by the said guide means comprising a plate pressed yieldingly against the said composite surface to be provided with the adhesive coating.

8. The apparatus defined in claim 6, further characterized by the said guide means comprising a plate detachably associated with means for pressing it yieldingly against the said composite surface to be provided with the adhesive coating.

9. In apparatus for applying a coating of adhesive in liquid state to paper and similar articles arranged in stepped formation in a continuous layer, so that a defined marginal portion of each article is left free with one surface exposed for coating, the combination with an adhesive container having a narrow outlet slit for adhesive and means for producing relative wiping action between the outlet slit of the container and the exposed composite surface formed by the said free marginal portions of the articles in the stepped layer, of guide means acting directly upon the said exposed composite surface in a zone preceding and immediately adjacent to the zone of application of the adhesive issuing from the

slit, supporting means for said stepped layer of articles, said supporting means directly confronting both the adhesive outlet of the container and the guide means, and means for projecting against said free marginal portions of said layer, in a direction forming an acute angle with the direction of travel of said layer, an air blast adapted to impinge on the successively passing free marginal portions and to press them firmly each against the corresponding subjacent sheet in the layer.

10. In apparatus for applying a coating of adhesive in liquid state to paper and similar articles arranged in stepped formation in a continuous layer, so that a defined surface portion of each article is exposed for coating, an adhesive container having an outlet for adhesive, means for supporting the said layer of articles, so that the stepped composite surface receiving the adhesive coating comes in close juxtaposition to the said adhesive outlet, means for producing relative wiping action between said adhesive outlet and said composite surface and guide means acting upon said composite surface in a zone preceding that in which it receives the adhesive, said adhesive outlet consisting of a duct of narrow, slit-like cross-section proceeding from the interior to the exterior surface of the adhesive container in a direction forming an acute angle with the direction from which the stepped layer of uncoated articles arrives at the said adhesive outlet and presenting a substantially linear slit-like opening in contact with said layer of articles, that side of the said opening over which the layer passes after receiving the coating being bounded by a blunt edge from which the external surface of the container recedes sharply, leaving only a linear strip of the container surface for contact with the coated composite surface of the layer.

11. The apparatus defined in claim 10, characterized by the said supporting means being organized to support the stepped layer along the path of travel of said layer to the adhesive applying zone and further characterized by the external surface of the container adjacent the slit-like adhesive outlet being shaped to recede gradually from the said supporting means and, therefore, from the uncoated composite layer surface, on that side of the said adhesive outlet from which the layer arrives.

12. The apparatus defined in claim 10, further characterized by the external surface of the adhesive container on that side of the slit-like adhesive outlet from which the uncoated stepped layer of articles arrives being shaped to recede gradually from the adhesive receiving composite surface of said layer, by the guide means acting on such surface consisting of a plate-like member having an edge portion disposed closely adjacent said receding external surface portion of said container, by supporting means for said plate-like member and by means associated with said supporting means for causing said edge portion of said plate-like member to press yieldingly upon the surface parts of the layer about to come into co-operation with the slit-like adhesive outlet.
